The ornamental design for single cable power inverter, as shown and described.

DESCRIPTION

FIG. 1 is a right side view of my single cable power inverter, the left side being a mirror image of this view.

FIG. 2 is a top view thereof.

FIG. 3 is a bottom view thereof.

FIG. 4 is a rear view thereof; and,

FIG. 5 is a front view thereof.

The broken line showings of the inverter housing and contacts in FIGS. 1, 2 and 3 are for illustrating purposes only and form no part of the claimed design.

The claim has been shown broken away for ease of illustration to show indeterminate length.
